ATTORNEY

UNITED STATES PATENT OFFICE

LEON WEINSTEIN, OF ST. LOUIS, MISSOURI

COMBINED SHOE SHANK STIFFENER AND HEEL BRACE

Application filed October 1, 1930. Serial No. 485,676.

This invention relates to a certain new and useful improvement in combined shoe-shank stiffeners and heel braces.

My invention has for its object the provision of an article or device of the type and for the purposes stated, which is simple in construction, which may be inexpensively manufactured, which may be easily attached to the shoe, which is durable in structure, and which is efficient in the performance of its intended functions.

And with the above and other objects in view, my invention resides in a novel feature of form, construction, arrangement, and combination of parts hereinafter described and pointed out in the claims.

In the accompanying drawing,—

Figure 1 illustrates a Cuban-heel shoe in outline in side elevation equipped with a combined shank-stiffener and heel-brace of my invention;

Figure 2 is a fragmental vertical sectional view of the so-equipped shoe;

Figure 3 is a transverse sectional view taken approximately on the line 3—3, Figure 1;

Figure 4 is a perspective view of the combined shank-stiffener and shoe-brace;

Figure 5 is a fragmental vertical sectional view of a Louis-heel shoe equipped with a slightly modified form of combined shank-stiffener and heel brace embodying my invention; and

Figure 6 is a perspective view of such modified shank-stiffener and heel-brace of my invention.

Referring now more in detail and by reference characters to the drawing, which illustrates practical embodiments of my invention, A designates a shoe of usual form and construction, of which 1 is the shank, and 2 is the heel, the former being relatively broad and flat, and the latter being of Cuban-type. B designates another shoe also of usual form and construction, of which 1' is the shank and 2' is the heel, the former, however, in this instance, being relatively narrow and outwardly convexed, and the latter being of the Louis type. Adapted for respective use with the shoes A and B, are the combined

shank-stiffeners and heel-braces C, C', best seen in Figures 4 and 6, of my invention.

The combined shank-stiffener and heel-brace C is constructed of any suitable relatively light-weight sheet or strip metal and, by the use of suitable stamping, punching, or other dies, is formed to integrally include a body portion *a* adapted to fit under the shoe-shank 1 and an extension *b* adapted to fit against the breast of the heel, the latter, for such purpose, projecting approximately at a right-angle from the portion *a* and being united thereto by a preferably gently curved or arcuate portion *c* adapted to fit over the break between the shank 1 and the heel 2, as best seen in Figure 1.

The stiffener-brace C is provided longitudinally adjacent its opposite side margins with a series of openings *d* for accommodating fastening nails or the like 3, and along its said opposite side margins is flanged or lipped, as at *e*, for edgewise biting, as it may be said, engaging the shoe under its attachment therewith by the nails 3. The engagement of the stiffener-brace C with the shoe is consequently tight and snug, the efficiency of the stiffener-brace in the performance of its functions being increased accordingly.

Intermediate its opposite side margins, the stiffener-brace C is longitudinally corrugated, as at *f*, as shown for strengthening purposes, and whereby also it is formed longitudinally with a central groove or channel *g*. The corrugations *f* and channel *g* preferably terminate short of the outer ends of the respective shank and heel portions *a*, *b*, as best seen in Figure 4, and in the channel *g* is lengthwise disposed a section of suitable wire or the like 4, which is spot-welded or otherwise united at its opposite ends to the stiffener-brace portions *a* and *b*. The member 4 is thus adapted to function as a re-enforcing member, in maintaining the form and rigidity of the stiffener-brace. As so constructed, I am enabled to employ relatively lighter weight strip metal in the construction of the compression member C than has heretofore, so far as I am aware, been

possible in the provision of efficient combined shank-stiffeners and heel-braces, the life of the punching and forming dies being consequently increased, the cost and labor of production being reduced, and the weight of the shoes to which my device is attached being lessened.

The combined shank-stiffener and heel-brace C' is structurally substantially similar to the stiffener-brace C, but in configuration is modified to similarly tightly and snugly bitingly fit the shoe B. To such end, its portion a' is longitudinally lengthened and arched and transversely convexed to correspond with shank 1', its portion b' rounded and concaved and its portion c' of greater arc to correspond with the breast of heel 2', all as shown. Hence, to avoid repetition, further detail description of the stiffener-brace C' is omitted, the detail description of the stiffener-brace C being applicable.

And it is to be understood that other changes and modifications in the form, construction, arrangement, and combination of the several parts of the combined shank-stiffener and heel-brace may be made and substituted for those herein shown and described without departing from the nature and principle of my invention.

Having thus described my invention, what I claim and desire to secure by Letters Patent is:

1. A metallic shoe shank-stiffener and heel-brace including a body member comprising a first portion adapted to fit in engaging relation under the shank, a second portion projecting angularly from one end of the first portion adapted to fit in engaging relation against the breast of the heel, and an intermediate arcuate portion uniting the first and second portions, and a longitudinally extending body-re-enforcing member fixed at its opposite ends to the said first and second portions and extending over said intermediate portion.

2. A metallic shoe shank-stiffener and heel-brace including a body member constructed of strip metallic material and formed to comprise a first portion adapted to fit in engaging relation under the shank, a second portion projecting angularly from an end of the first portion adapted to fit in engaging relation against the breast of the heel, and an intermediate arcuate portion uniting the first and second portions, and a longitudinally extending body-re-enforcing member constructed of wirelike material permanently joined at its opposite ends to said first and second portions and fitting over said intermediate portion.

3. A metallic shoe shank-stiffener and heel-brace including a body member constructed of strip metallic material and formed to comprise a first portion adapted to fit in engaging relation under the shank, a second portion

projecting angularly from an end of the first portion adapted to fit in engaging relation against the breast of the heel, and an intermediate arcuate portion uniting the first and second portions, and a longitudinally extending body-re-enforcing member of circular section spot-welded at its opposite ends to said first and second portions and fitting over said intermediate portion.

4. A metallic shoe shank-stiffener and heel-brace including a longitudinally channeled body member of strip metallic material and comprising a first portion adapted to fit in engaging relation under the shank, a second portion projecting angularly from an end of the first portion adapted to fit in engaging relation against the breast of the heel, and an intermediate arcuate portion uniting the first and second portions, and a body-re-enforcing member of circular section fitting in said channel and over said intermediate portion and fixed at its opposite ends to the said first and second portions.

5. A metallic shoe shank-stiffener and heel-brace including a longitudinally channeled body member constructed of strip metallic material and comprising a first portion adapted to fit in engaging relation under the shank, a second portion projecting angularly from an end of the first portion adapted to fit in engaging relation against the breast of the heel, and an intermediate arcuate portion uniting the first and second portions, and a body-re-enforcing member of circular section fitting in said channel and over said intermediate portion and at its opposite ends permanently fixed to the said first and second portions, said body member having shank and heel biting flanges along its opposite side margins and being also provided adjacent said margins with series of nail-accommodating apertures.

In testimony whereof, I have signed my name to this specification.

LEON WEINSTEIN.
